US00D597832S

(12) **United States Design Patent**
Bischoff et al.

(10) **Patent No.:** **US D597,832 S**
(45) **Date of Patent:** **** Aug. 11, 2009**

(54) **CONTAINER**

(75) Inventors: **Corey Michael Bischoff**, Cincinnati, OH (US); **Julie Jane Baker**, Hamilton, OH (US); **Daniel Adam Streng**, Elmwood Park, IL (US); **Timothy Ryan Read**, Chicago, IL (US); **Parker David Selbert**, Chicago, IL (US); **Christopher Richard Streng**, Chicago, IL (US); **James Louis Capo**, Middletown, OH (US)

(73) Assignee: **The Procter & Gamble Company**, Cincinnati, OH (US)

(**) Term: **14 Years**

(21) Appl. No.: **29/291,462**

(22) Filed: **Nov. 13, 2007**

(51) **LOC (9) Cl.** **09-03**

(52) **U.S. Cl.** **D9/431**

(58) **Field of Classification Search** D9/430–433, D9/414, 418, 420–423, 435, 560, 561, 711; D3/201, 272, 273, 305; 206/278, 297, 299, 206/320, 339, 433, 769, 770, 775, 776, 781, 206/782, 822, 155; 229/100, 103.3, 104–106, 229/107, 108, 108.1, 110, 111, 112, 115, 229/117.16, 120, 125.015, 120.32, 133.24, 229/122.29, 124, 160.1, 162.1, 162.6, 163, 229/182.1, 201, 406, 407, 902, 904, 906, 229/922, 930, 939, 942

See application file for complete search history.

(57) **CLAIM**

The ornamental design for a container, as shown and described.

DESCRIPTION

FIG. 1 is a perspective view of a container, showing our new ornamental design.

FIG. 2 is a front view of the container of FIG. 1.

FIG. 3 is a back view of the container of FIG. 1.

FIG. 4 is a right side view of the container of FIG. 1.

FIG. 5 is a left side view of the container of FIG. 1.

FIG. 6 is a top view of the container of FIG. 1; and,

FIG. 7 is a bottom view of the container of FIG. 1.

1 Claim, 6 Drawing Sheets
